UNITED STATES PATENT OFFICE.

JOSEPH S. HAYS, OF ANNAPOLIS, MARYLAND, ASSIGNOR TO J. S. HAYS
AND DANIEL W. DORSEY, OF SAME PLACE.

IMPROVEMENT IN IRONING-TABLES.

Specification forming part of Letters Patent No. **170,366**, dated November 23, 1875; application filed November 3, 1875.

To all whom it may concern:

Be it known that I, JOSEPH S. HAYS, of Annapolis, in the county of Anne Arundel and State of Maryland, have invented certain new and useful Improvements in Ironing-Tables; and I do hereby declare that the following is a full, clear, and exact description thereof, reference being had to the accompanying drawings, and to the letters of reference marked thereon, which form part of this specification.

The nature of my invention consists in the construction and arrangement of an ironing-table, as will be hereinafter more fully set forth.

In order to enable others skilled in the art to which my invention appertains to make and use the same, I will now proceed to describe its construction and operation, referring to the annexed drawing, in which—

Figure 1 is a plan view. Fig. 2 is a central vertical section on line *x x*, Fig. 1. Fig. 3 is a cross-section on line *y y*, Fig. 1; and Fig. 4 is a detail view of my invention.

A represents the ironing-board, made of the ordinary form—that is, smaller at one end than at the other. The board *A* is divided longitudinally from the smaller end of the board for a suitable distance inward, and one part, *A'*, then cut across at right angles, as shown. The part or leaf *A'* is hinged to the main part, in such a manner that, when desired, it can be folded underneath, for ironing shirts, pantaloons, or other similar articles. Near the larger end of the board *A*, on the under side, are secured two T-shaped irons, *a*, the center-pieces of which extend vertically downward. To the outer side of each iron *a* is pivoted a leg, *B*, the two legs being connected by a cross-bar, *B'*, and the same pivot connects or pivots a brace, *C*, on the inner side of each iron. At a suitable distance be-

low the board *A*, on the inner side of each leg *B*, is pivoted another brace, *D*, which crosses the brace *C*. The brace *C* is slotted for a suitable distance longitudinally, and a headed rivet or bolt, *b*, is passed through the slot into the brace *D*, to connect the two. At the ends of the braces *D* are hinged the legs *G G*, which are connected by a cross-bar, *G'*; and the ends of the braces *C C* are provided with notches *x x*, to fit over the upper edge of said cross-bar, and thus firmly brace the supporting-frame of the ironing-table.

Instead of using slots in the braces *C*, these braces may pass through slides *d*, swiveled to the braces *D*, which will answer the same purpose.

On top of the board *A*, near the large end, is fastened an iron-stand, *E*, provided with upward-projecting flanges *e* around the sides and back, to prevent the iron from falling off when the board is raised on its hinges.

Having thus fully described my invention, what I claim as new, and desire to secure by Letters Patent, is—

1. The ironing-board *A*, cut to form a longitudinal leaf, *A'*, hinged to the board, capable of being turned under the same, for the purposes herein set forth.

2. The combination, with an ironing-board, of the legs *B B*, braces *C C*, having slots *x x*, braces *D D*, and legs *G G*, with cross-bar *G'*, substantially as and for the purposes herein set forth.

In testimony that I claim the foregoing as my own I affix my signature in presence of two witnesses.

JOSEPH S. HAYS.

Witnesses:

JAMES A. MEDLEY,
JAMES E. RYAN.
